UNITED STATES PATENT OFFICE.

ROSCOE W. UPP, OF CHICAGO, ILLINOIS, ASSIGNOR OF ONE-HALF TO CHARLES T. JACOBS, OF CHICAGO, ILLINOIS.

DENTAL DEVICE.

1,180,745.

Specification of Letters Patent. Patented Apr. 25, 1916.

Application filed January 29, 1916. Serial No. 75,058.

To all whom it may concern:

Be it known that I, Roscoe W. Upp, a citizen of the United States, residing at Chicago, in the county of Cook and State of Illinois, have invented certain new and useful Improvements in Dental Devices, of which the following is a description.

In the proper fitting of artificial teeth to the mouth of the user, it is customary, after 10 setting the teeth in wax, to grind them down so that they will match—the upper and lower—thus making provision for the proper matching of the teeth in both what is called the protrusive bite, or an endwise 15 movement of the upper and lower teeth, and also the proper matching of the two sets in what might be termed the lateral bite, or a partial transverse movement of one set upon the other during the masticating operation. 20 This is to secure what is termed in the art, a balancing effect. This grinding down process, as heretofore practised, has been accomplished by placing the teeth in wax, and thence in an articulator of well 25 known form, after which the operator placing vaseline, oil and emery dust between the meeting faces of the teeth of the two sets, proceeds with a grinding movement accomplished by hand, the two sets being held in 30 the relative position that they would occupy in the mouth of the user by the articulator. Thus, as the meeting parts of the teeth are ground down, to match one with the other, and to balance, closely approaching the effect 35 of the natural teeth in the mouth.

The object of my invention is to secure a proper endwise, as well as lateral movement of the teeth while thus held in an articulator, and for the purpose stated, in a simple and effective manner, thus disposing 40 with hand operation for this purpose and greatly reducing the cost of construction.

To this end my invention consists in the novel construction, arrangement and combination of parts herein shown and described, 45 and more particularly pointed out in the claims.

In the drawings, wherein like reference characters indicate like or corresponding parts, Figure 1 is a side elevation of one simple form of my invention, substantially on line 1—1 of Fig. 2, showing a part of an articulator of well known form as connected to my improved device; Fig. 2 is 50 substantially a plan view of the same; Fig. 3 is also a plan view, showing the parts in

position, and the position of the articulator as one set of teeth is moved transversely to the other for the purpose stated; Fig. 4 is a rear view of the articulator, taken substantially on line 4—4 of Fig. 3; Fig. 5 is a partial section taken substantially on line 5—5 of Fig. 4; Fig. 6 is a partial sectional view of the rear part of an articulator, showing one simple way in which connection is made therewith to secure the operation described; Fig. 7 is a fragmentary view also showing simple adjustable means by which connection can be made with the rear part of the articulator; Fig. 8 is a plan view showing means for so grinding a plurality of sets of teeth at the same time.

As shown in the drawings, referring particularly to Fig. 1, 1 and 2 represent the upper and lower parts of a suitable articulator, the two parts being connected in any well known or usual manner for resiliently maintaining the parts in proper relative position one to the other. 3 represents the wax for holding the teeth, and 4 represents the teeth so positioned. As I claim nothing new in the articulator, it is not deemed necessary to go into the details of construction of such devices, as they are well known in the art. These devices are arranged to secure the proper relative movement of the two parts 1 and 2, both in a protrusive or backward and forward movement, and in a lateral movement, as before stated. 5 is a suitable base carrying upon it suitable 80 standards 6—6.

The articulator is supported in the standards 6, the ends of the transverse part 7 being seated in suitable bearings formed in the standard 6 for that purpose. In the form shown a strap or suitable part 8 clearly shown in Figs. 1, 2 and 4, extends from one standard to the other, and connects the tops of the two together. A resilient member or spring 9 extends from the rearwardly extending part 10 up to, and is connected to the connecting strap 8, normally tending to resiliently hold the part 2 down in forward contact with the part 1, as shown. The connecting part 11 (Figs. 2, 4 and 6) extends from one downwardly projecting extension 12 to the other, said extension being connected with the lower part 1 of the articulator, and a spring 13 extending from the center thereof is carried back 100 and attached to the base 5, as at 14, thus resiliently holding the part 1 to its lower

limit of movement. In a construction of this kind the resiliency of the connection of the parts and their movement is desirable.

15 is a suitable support of any preferred arrangement carried on the base 5, and having mounted therein suitable belt pulleys 16-17, or equivalent members for the purpose hereafter pointed out. The shaft carrying the pulley 16 shown in the drawings as 10 being forward or nearer to the articulator, is positioned in suitable bearings on the parts 15, or their equivalent for the purpose, and outside of the line of said support are transversely bent in opposite directions, as clearly indicated in Figs. 2 and 3. Said shaft is indicated by the numeral 18 and the lateral bends 19-20. Suitable means extend from the end of the bends or crank-shafts 19-20 to the articulator, and are preferably connected 15 to the upper member 2 thereof on opposite sides, as shown. It will thus be seen that as the pulley 16 is rotated, in any desirable or preferred manner, the member 2 of the articulator will be partially pulled 20 transversely, first in one direction and then in the other across the mating part 1, securing a grinding effect in that direction. As shown in Figs. 1, 2 and 3, the connection from the cranks 19-20 to the articulator, 25 consists of the chains 21, one of which is attached on each side of the pulley, as shown. It is preferable in a device of this kind that means should be provided to adjust the length of the chains 21, to provide 30 for any variance of the distance caused by the use of differently constructed articulators or plates, there being many on the market at the present time which could be used with my improved device.

40 As shown in the drawings, the pulley 16 is driven by a belt extending from a reduced pulley 22 carried on the shaft 24, on which the pulley 17 is mounted, a suitable belt, as 45 driving the pulley 17 from a suitable source of power. The shaft 24 is preferably formed at its ends with transverse bends 26-27, which are bent substantially parallel to one another, and extend in the same direction. The shafts 18 and 24 are preferably retained in their bearings by plates 28 50 retaining them in proper position, which may readily be moved to disengage the shafts, when the belts being released the shafts can be transposed, with the pulley 17 placed forward in the position the pulley 16 occupied, while the pulley 16 is moved rearwardly to the position formerly occupied by pulley 17, and the shafts properly maintained in their bearings. Pulley 16 has in 55 proximity thereto a reduced pulley 23, similar to the reduced pulley 22 on the shaft 24, and for the same purpose.

When the shaft 24 is moved forward, as indicated, and the chains 21, or their equivalents, are attached to the crank ends 26-27

of said shaft, the rotation of the pulley will cause a straight pull rearwardly on both sides of the part 2 of the articulator, which, owing to the resilient connections described, will, as it is released from the ends of the 70 pull, spring forward into normal relation with the co-operating part. This will provide for the operation which I have referred to, and the teeth, when ground in this manner, as well as when ground laterally, as 75 stated, will be found to be perfectly matched, and to properly co-operate and co-act in the operation of mastication, when used.

It is obvious that any suitable supports providing bearings for the pulleys may be 80 provided, whether the same be by disconnected standards (not shown) or by a single block on each side, as shown in the drawings. It is also obvious that the supports 6 for the articulator may be of any preferred 85 form of construction to secure the results mentioned. As shown in Fig. 5, the standards 6 are provided with a plurality of bearings 29, in any one of which the parts 7 of the articulator may be located, thus arranging for the partial vertical adjustment of the articulator to secure the most desirable relative position to the actuating devices co-operating therewith. The standard 6 shown to the left of Fig. 4 is preferably hinged, as 90 at 30, whereby when the strap 8 is released, the said standard may be opened, as shown in dotted lines in Fig. 4, and the articulator readily removed and another replaced therein, as desired.

The connection of the forward ends of the chains 21 with the articulator may be in any preferred manner. With the articulators now on the market, and particularly adapted to be employed in my improved device, some 105 suitable form of clamps 31, may be used, which may be clamped directly to a suitable part of the articulator, and have suitable apertures therethrough, or other means for the connection of the forward ends of the 110 chains. A limited adjustability of the clamps on the articulator is thus possible. As a general rule, however, simple adjustable means may be provided by threading the chain through a suitable eye 32 in the 115 articulator or clamp, as shown in Fig. 7, where a hook on the end of the chain permits the latter to be shortened or lengthened, as desired, by connecting the hook with different links of the chain.

As shown in Fig. 8, a plurality of said articulators may be suitably supported in standards 33, while a bar 34, or equivalent means, connects with all of them, and at its other end is attached to a wrist pin 35 120 carried on the pulley 36 mounted upon the shaft 37, a belt 38 driving the shaft, or equivalent means be employed for the same purpose. As thus shown it becomes clear 125 that the articulators may be mounted so that

the said grinding movement may be performed upon a plurality thereof at one time.

Having thus described my invention, it is obvious that various immaterial modifications may be made in the same without departing from the spirit of my invention; hence I do not wish to be understood as limiting myself to the exact form, construction, arrangement and combination of parts hereinafter shown and described, and uses mentioned.

What I claim as new and desire to secure by Letters Patent is:—

1. In a device of the kind described, a dental articulator constructed to resiliently maintain the two plates in contact with one another, in combination with mechanism arranged to alternately pull upon the sides thereof, means for driving said mechanism, and means for connecting the same with each side of one of the members of the articulator.

2. In a device of the kind described, a dental articulator provided with means for resiliently maintaining the two plates in contact with one another, in combination with mechanism arranged to alternately pull and yield upon a part, means for driving said mechanism, and means for connecting said pulling mechanism with one of the members of the articulator, whereby a direct pull upon one of the parts is provided, causing the plates to grind one upon the other to produce the protrusive bite.

3. A device of the kind described, comprising a dental articulator provided with means for resiliently holding the two plates together, in combination with mechanism arranged to alternately pull, first upon one side and then upon the other, or at will to simultaneously pull directly upon both sides at the same time, and means connecting said mechanism with one of the members of the articulator at will, to produce either a longitudinal movement of one member on the other or a lateral movement thereof.

4. In a device of the kind described, a dental articulator constructed to resiliently maintain the two plates in contact with one another, in combination with mechanism arranged to alternately pull upon the sides of one of the members of the articulator, adjustable means for connecting said mechanism with one member of the articulator, and means for driving said mechanism.

5. A device of the kind described, comprising a dental articulator, a suitable frame for carrying the standards for supporting the articulator, provided with means for adjustably supporting the articulator at different points of elevation thereon, in combination with a rotatable shaft formed with crank shafts at each end thereof, means for

rotating said shaft, and means for connecting the crank shafts with one of the plates of the articulator.

6. A device of the kind described, comprising a dental articulator, and means for supporting the same, in combination with a rotatable shaft having its ends formed into oppositely formed crank shafts, means for supporting said shaft and rotating the same, and means for adjustably connecting the ends of the crank shafts with one of the plates of the articulator.

7. A device of the kind described, comprising a dental articulator, and means for supporting the same, in combination with a rotatable shaft, having its ends extended to form crank shafts extending in the same general direction, means for supporting and rotating the shaft, and means for connecting the crank shafts with one plate of the articulator.

8. A device of the kind described, comprising a dental articulator, and resilient means for maintaining the two in relative positions with one another, standard supports for the articulator, means for regulating the vertical adjustment of the articulator thereon, one of said standards being pivotally connected to the base, whereby it may be opened to release the articulator, a locking member connecting the tops of the two standards, and resilient means for connecting the upper plate of the articulator with said locking means, normally resiliently forcing the upper plate upon the lower, in combination with mechanism for alternately longitudinally pulling said upper plate upon the lower plate, and then releasing the same, or for alternately pulling first upon one side of said plate and then upon the other to produce a lateral movement of the upper plate upon the lower, at will, substantially as described.

9. A device of the kind described, comprising a suitable base provided with means for supporting a plurality of dental articulators, in proximity to one another, the plates of said articulators being resiliently maintained in contact with one another, in combination with mechanism producing a reciprocal movement, means for driving said mechanism, and means for connecting the same with said articulators, whereby one plate of each of said articulators is relatively moved upon its mating member, substantially as described.

In testimony whereof, I have hereunto signed my name in the presence of two subscribing witnesses.

ROSCOE W. UPP.
